ROTARY OVEN

William A. Roberts and William Spiegel,
Butte, Mont.

Application September 8, 1942, Serial No. 457,684

1 Claim. (Cl. 107—59)

This invention relates to rotary ovens.

An object of this invention is to provide a rotary oven in which the heat is derived from electric heaters.

Another object of this invention is to provide an improved rotary carrier for the articles which are being baked.

A further object of this invention is to provide a rotary oven which includes a supporting frame embedded in heat insulated walls so that the interior of the oven may be kept clean.

A further object of this invention is to provide an oven of this kind having transparent panels in opposed walls, one of the panels being hingedly mounted and constituting a collapsible shelf for supporting the trays which are placed into or removed from the oven.

A further object of this invention is to provide an oven of this kind in which the carrier is formed of a pair of spider elements mounted on a rotary shaft, and tray supports pivotally carried by the arms of the spider elements, the tray supports being formed of angle iron about three sides thereof and triangular end pieces which are pivoted to the arms of the spider elements so that the tray supports will remain in a horizontal position during rotation of the carrier.

With the foregoing objects and others which may hereinafter appear, the invention consists of the novel construction, combination and arrangement of parts as will be more specifically referred to and illustrated in the accompanying drawings, wherein is shown an embodiment of the invention, but it is to be understood that changes, variations and modifications may be resorted to which fall within the scope of the invention as claimed.

In the drawings:

Figure 1 is a detail side elevation partly broken away and in section of a rotary oven structure constructed according to an embodiment of this invention.

Figure 2 is a detail rear elevation partly broken away and in section of the device.

Figure 3 is a detail side elevation partly broken away of the rotary carrier supporting frame structure which is embedded in the heat insulated side walls of the device.

Figure 4 is a plan view of one of the tray carriers.

Figure 5 is a sectional view taken on the line 5—5 of Figure 1, and

Figure 6 is a fragmentary front elevation of the front wall of the housing.

Referring to the drawings, the numeral 10 designates generally a heat insulated housing which is formed of opposite side walls 11 and 12, front and rear walls 13 and 14 respectively 5 and a substantially semi-circular top wall 15. The housing 10 is formed of an inner jacket 16 which is preferably of metallic construction and of an outer jacket 17. The two jackets 16 and 17 are spaced from each other and a heat insulating means 18 is interposed between the two jackets 16 and 17.

The front wall 13 has a transparent panel 19 secured thereto by means of removable fastening members 20. The panel 19 is mounted in a rectangular metal frame 21 and is provided for the purpose of permitting persons to look into the interior of the housing 10 in order to see the articles which are being baked and also to determine the character of the baking.

20 The rear wall 14 is provided with a hinged panel 22 which is mounted in a rectangular frame 23, and the panel 22 is hingedly mounted at its lower edge as at 24. The panel 22 comprises a hinged window and also a shelf on which the trays may be placed prior to or subsequent to the positioning of the trays in the interior of the housing 10. The panel 22 is adapted to be maintained in a horizontal shelf forming position as shown in Figure 1 by means of a pair 25 of pivoted arms 25 which are pivoted as at 26 to the opposite ends of the frame 23. The lower ends of the arms 25 are slidable in guides 27 which are secured to the outer face of the rear wall 14.

35 One of the side walls 11 has hingedly secured thereto upper and lower doors 28 and 29 which permit ready access to the interior of the housing 10 in order to clean the housing or for other purposes. By providing the two doors 28 and 40 29 a selected one or both of these doors may be opened to permit the desired access into the housing. The housing 10 has embedded in the two side walls thereof a frame structure, generally designated as 30. The frame structure 30 45 comprises two upright frame members 31 and 32. The frame member 31 includes a lower horizontal frame bar 33 which is formed of angle iron and also is formed of an upper horizontal flat frame bar 34. A pair of vertically 50 disposed angle frame members 35 are secured between the lower and upper horizontal frame bars 33 and 34, and a pair of upwardly converging bracing angle members 36 and 37 are 55 also secured between the lower and upper frame

members 33 and 34 and are secured in any suitable manner to the vertical angle members 35.

The frame structure 32 comprises a lower horizontal frame member 38 of angle construction and an upper horizontal flat frame bar 39. The frame members 38 and 39 are held in spaced apart relation by means of a pair of vertical angle frame members 40 and 41. The frame members 40 and 41 are secured to the frame members 38 and 39 and coact with these frame members in providing a door opening for the two doors 28 and 29. A pair of upwardly convergent bracing members 42 and 43 are secured at their lower ends to the horizontal frame member 38 and are secured at their upper ends to the vertical doorway forming frame members 40 and 41, respectively. As shown in Figure 2, the two frame members 31 and 32 are adapted to be embedded in the heat insulating means between the inner and outer shells or jackets 16 and 17 so that the interior of the housing 10 will be free of any obstructing frame members. The upper horizontal bars 34 and 39 have secured thereto bearing members 44, and preferably, one of the side walls 11 is formed with an opening 45 which provides access to at least one of the bearings 44. A carrier shaft 46 is journaled in the two bearings 44 extending across the housing 10 between the side walls 11. The shaft 46 at one end extends exteriorly of the housing 10 and has secured thereto a sprocket 47. The shaft 46 is adapted to be rotated by means of a power member 48 in the form of a motor or the like which has secured to the drive shaft 49 thereof a driving sprocket 50. A chain or other flexible drive member 51 is trained about the driving member 50 and the driven member 47.

The shaft 46 has fixedly secured thereto within the housing 10 a pair of spider members 51 and 52. The spider members 51 and 52 are of like construction and each includes a central hub 53 which has formed integral therewith a plurality of radially arranged arms 54. The two spider members 51 and 52 are so arranged that one arm 54 thereof will be disposed in the same plane as an associated arm of the spider member 52. The pairs of associated arms 54 of the two spiders 51 and 52 have dependently and pivotally secured therebetween tray carriers or supports 55. The tray carriers or supports 55 are constructed, as shown in Figure 4, of a rear angle bar 56, a pair of side-angle bars 57 and a forward flat bar 58. The flat bar 58 is secured at the opposite ends thereof to a connecting plate 59 which underlies the adjacent horizontal side of a side member 57 and is secured thereto by fastening devices 60 or the like in the form of rivets. The vertical sides 61 of the side members 57 have fixed thereto upstanding triangular side plates 63. The side plates 63 at their upper ends or apices thereof have formed integral therewith an upwardly extending stem 64 which is pivotally secured by means of a pivot member 65 to a spider arm 54. The flat bar 58 forms an open end of the skeleton frame formed by the angle members 56 and 57 so that the trays supporting the edibles may be moved over the flat bar 58 into the carrier 55.

The housing 10 has mounted in the lower portion thereof and below the circle described by 70

the rotation of the tray carriers a pair of electrical heating elements 66. The heating elements 66 are controlled by means of a thermostat 67 which has one side thereof connected by means of a conductor 68 to the heating elements 66 and the other side of the thermostat 67 is connected by means of a conductor 69 to an input connection 70. The input connection 70 is connected by means of a conductor 71 to the other side of the heating element 66. The thermostat 67 may have a shaft 72 connected therewith which terminates at its outer end exteriorly of the housing 10 and may be provided with an indicating arm or pointer 73 so that the thermostat 67 may be manually adjusted as to its operation exteriorly of the housing 10. The housing 10 may also have mounted on the interior thereof a pair of light bulbs 74 which are mounted in sockets 75 secured to the side wall 11. 20 The top wall 15 of the housing 10, preferably, has a vent tube 76 mounted therein so that the fumes from the interior of the housing 10 may, if desired, be carried off to a suitable point remote from the housing. 25 In the use and operation of this oven, the heaters 66 are connected to a suitable source of electric current supply through the input connection 70. The rotation of the motor 48 will rotate the carrier structure including the two spiders 51 and 52, and the several tray carriers 55 which are pivotally and dependently supported from the arms 54 of the spiders 51 and 52 will be maintained in a horizontal position throughout the rotation of the spiders 51 and 30 52 by the depending supports for these tray carriers. The heating elements 66 may be of a character to provide several different degrees of temperature within the housing 10 and such degrees may be regulated through the medium of the thermostat 67. 35

By providing the supporting structure for the rotary tray carriers as herein disclosed, the interior of the housing 10 can easily be cleaned and by insulating the entire housing 10, the heat generated from the heaters 66 will be retained within the housing. This rotary oven may be of a size such that it may be mounted in a store window or the like so that the customers may see the articles as they are being baked. 40

What we claim is:

A rotary oven comprising a heat insulated housing formed of opposite side, front and rear walls, and a substantially semi-circular top wall, said walls including inner and outer jackets and heat insulating means between said jackets, a carrier support comprising a pair of upstanding frame members embedded in the insulation of said side walls, a rotary shaft carried by the upper portions of said members and extending through said oven, and a rotary carrier means fixed to said shaft, each frame member comprising upper and lower horizontal angle members, a pair of vertical angle members secured between said horizontal angle members and inwardly from the ends of the latter, and upwardly convergent bracing members extending upwardly from said lower horizontal angle member. 55
